CLAIM

The ornamental design for a watch, substantially as shown and described.

DESCRIPTION

FIG. 1 is a top-left perspective view of a watch showing my new design;
FIG. 2 is a top plan view thereof;
FIG. 3 is a left side elevational view thereof, the right side being similar but without the buttons;
FIG. 4 is a rear elevational view thereof;
FIG. 5 is a bottom plan view thereof.

*Fig. 1**Fig. 2**Fig. 4**Fig. 3**Fig. 5*
